Primary Examiner — John A Voytek(57) **CLAIM**

The ornamental design for a tire, as shown and described.

DESCRIPTION

FIG. 1 is a side perspective view of a tire showing our new design, it being understood that the tread pattern is repeated throughout the circumference of the tire, the opposite side being the same as that shown;

FIG. 2 is a front elevational view of the tire;

FIG. 3 is a side elevational view of the left side of the tire;

FIG. 4 is a side elevational view of the right side of the tire;

FIG. 5 is an enlarged fragmentary view of FIG. 2;

FIG. 6 is a first transversal section view of the tire taken along line 6-6;

FIG. 7 is a second transversal section view of the tire taken along line 7-7; and,

FIG. 8 is an enlarged fragmentary view of FIG. 2 with section lines related to views 6-6 and 7-7.

The broken lines defining the sidewall and inner bead depict environmental subject matter that forms no part of the claimed design.
